UNITED STATES PATENT OFFICE.

ALBERT C. GOEDDEL, OF PITTSBURG, PENNSYLVANIA, ASSIGNOR TO W. GORDON MILLER.

ATTACHMENT FOR COOK-STOVES.

SPECIFICATION forming part of Letters Patent No. 513,967, dated January 30, 1894.

Application filed December 28, 1892. Serial No. 456,568. (No model.)

To all whom it may concern:

Be it known that I, ALBERT C. GOEDDEL, a citizen of the United States, residing at Pittsburgh, in the county of Allegheny and State 5 of Pennsylvania, have invented certain new and useful Improvements in Attachments for Cook-Stoves; and I do hereby declare the following to be a full, clear, and exact description of the invention, such as will enable others skilled in the art to which it pertains to make and use the same, reference being had to the accompanying drawings, which form a part of this specification.

My invention relates to an improved attachment for cook stoves using gas for fuel, and consists in certain details of construction and combination of parts as will be fully described hereinafter.

In the accompanying drawings, Figure 1 is 20 a plan view of my improved device which is constructed in accordance with my invention. Fig. 2 is a plan view of the under pan, showing a portion of the top revolved about its pivotal point. Fig. 3 is a sectional side 25 elevation of my improved device, said section taken on the line X—X.

To put my invention into practice I provide a pan 1 of a suitable size and form of construction, and adapted to fit into the top 30 of an ordinary cook stove by removing four of the lids and the cross piece of the same. This pan 1 is provided with a slide valve 3 located at the rear, for the purpose of creating a draft to the chimney if so desired. Attached to the top of the pan 1 by means of a removable pivot 7 is a top piece 4 consisting 35 of a plate having four annular openings 5 formed therein of the same size as the lids of the stove upon which my improved device is used. These openings 5 are covered with the lids removed from the stove, and each opening provided with a burner 6, and independent branch pipe 9 leading to the main supply pipe 8. Each of these branch pipes 9 is 45 provided with a valve 11 operated by a hand

lever 12. This lever 12, may be adjusted to various positions to regulate and control the flow of gas to the burner, by means of a spring 50 rack 13. It will be obvious that by means of the removable pivot this swinging top can be removed or detached for any purpose at any time.

This apparatus is placed on the stove and may be removed if the gas becomes exhausted by disconnecting a flexible tube which 55 conducts the gas into the main pipe 8, and the apparatus may be used as a garbage burner by placing the refuse from the table in the bottom of the pan 1 and opening the slide valve 3 at the rear to permit the waste products of combustion to escape into the chimney. This valve 3 is opened when it is desired to heat the water back at the rear of the stove.

Having thus described my invention, what 65 I claim, and desire to secure by Letters Patent, is—

An attachment for gas stoves comprising a metallic pan or casing fitted to the top of the stove and forming the top portion thereof 70 and projecting down into the stove a prescribed distance to form a housing for the burners and other parts; a hinged lid or cover for the pan or casing provided with ports or openings to receive the ordinary 75 stove lids or covers, and removably pivoted to said pan or casing; a gas burner under each port or opening; a branch supply-pipe for each burner; a controlling valve for each branch pipe; and a draft regulator covering 80 and opening into the casing, which communicates with the chimney.

In testimony that I claim the foregoing I hereunto affix my signature this 11th day of November, A. D. 1892.

ALBERT C. GOEDDEL. [L. S.]

In presence of—

M. E. HARRISON,
ALBERT J. WALKER.
